(No Model.)

M. QUINLAN.

CHAIN WRENCH.

No. 373,603.

Patented Nov. 22, 1887.

UNITED STATES PATENT OFFICE.

MAURICE QUINLAN, OF GLENDALE STATION, NEW YORK.

CHAIN-WRENCH.

SPECIFICATION forming part of Letters Patent No. 373,603, dated November 22, 1887.

Application filed March 24, 1887. Serial No. 232,227. (No model.)

To all whom it may concern:

Be it known that I, MAURICE QUINLAN, of Glendale Station, Queens county, State of New York, have invented certain new and useful 5 Improvements in Chain-Wrenches, of which the following is a specification.

This invention relates to certain new and useful improvements in that class of wrenches constructed with curved serrated jaws and 10 with a chain that encircles the pipe.

The object of my invention is to provide a new and improved chain-wrench which can be reversed very easily and rapidly, and in which the handle can be adjusted to any 15 desired inclination to the jaws, thus facilitating the using of the wrench in narrow trenches.

The invention consists of the combination, with two jaws, of a handle between the same, which handle may be locked at different in- 20 clinations to the longitudinal axis of the jaws, and of a chain held between the jaws, all as will be fully described and set forth hereinaf- 25 ter, and finally pointed out in the claims.

In the accompanying drawings, Figure 1 is a 25 side view of my improved chain-wrench. Fig. 2 is a horizontal sectional view. Fig. 3 is a longitudinal sectional view on the line *x*-*x*, Fig. 2. Fig. 4 is a cross-sectional view on the line *y*-*y*, Fig. 2. Fig. 5 is a detail top view of a part of 30 the handle, showing a different construction of the hook. Fig. 6 is a detail side view of part of the handle, showing a modification. Fig. 7 shows a modified construction.

Similar letters of reference indicate corre- 35 sponding parts.

The two jaw-plates A have curved serrated edges B, the said plates being shaped approxi- 40 mately as shown. They are united by a bolt, C, which is passed through an eye in the end 45 of the handle-bar C', inserted between the plates. Said bolt C is also passed through the apertures in two links, E, which are placed on opposite faces of the handle-bar C', as shown in Fig. 3, and between the swinging ends of 50 said links one end of a link-chain, F, is fastened, thus adapting the link-chain to swing between the jaw-plates. The jaw-plates are also provided with a series of apertures, G, ar- 55 ranged on a semicircular or segmental line at the ends of the plates opposite those having the serrations, and the handle-bar is provided

with an aperture, H, the distance of which from the aperture in the end of the handle-bar is equal to the radius of the line of apertures G. A bolt, J, is passed through two corre- 55 sponding apertures G in the jaw-plates A, and through the aperture H of the handle-bar.

As shown in Fig. 6, the handle-bar C' is pro- 60 vided with laterally-projecting prongs T, which are curved, and between which a longitudinal recess is formed for engagement with the link of a chain, as shown in dotted lines in Fig. 6; or in place of this construction the construc- 65 tion shown in Figs. 1, 2, 3, and 5 may be used, which is as follows: On opposite faces of the 70 handle-bar links K are provided, through which the pin or bolt J also passes, and to the swinging ends of said links the forked hook L is pivoted, as shown in Fig. 5. Ordinarily, the jaws are held in such a position that their 75 longitudinal axis is in line with the longitudi- 80 nal axis of the handle-bar, which is accom- plished by passing the bolt through the middle aperture of each segmental row of apertures G, as shown in Fig. 1. The link-chain F is 85 passed around the pipe, upon which a serrated edge rests, and the chain drawn taut and then engaged with the forked end of the hook L or the prongs T.

When it is desired to work in a narrow 80 trench, the handle-bar must be at an inclina- 85 tion to the longitudinal axis of the jaw-plates. To accomplish this the bolt J is withdrawn, and the handle-bar is adjusted to the proper angle and locked in place by passing the bolt 90 through corresponding apertures in the han- 95 dle-bar and plates A. When it is desired to reverse the implement, the bolt J is withdrawn, the handle removed and then reversed, so that the lugs T will project from the opposite side edge; or, in case the hook L is used, the links K are removed and placed on the other side of the handle-bar. The chain E need not be dis- engaged or detached for reversing the imple- 95

The same tool may be used for large and small pipes, as the chain can be drawn taut and held at any desired length by the forked hook L. In place of providing the apertures G, a series of parallel radial ribs forming pockets, as shown 100 at M, may be provided on the inner sides of the jaws. The bolt J is used to hold the jaw.

plates together, and also to hold the fixed end of the chain. The handle is not pivoted on the jaws, but is inserted between different pairs of ribs, according to the desired angle of inclination of the same to the jaws.

Having thus described my invention, I claim as new and desire to secure by Letters Patent—

1. In a chain-wrench, the combination, with two jaw-plates, of a handle held adjustably at different inclinations to the jaw-plates between said jaw-plates, which handle has laterally-projecting prongs, and of a chain having one end held between the jaw-plates, substantially as shown and described.
- 15 2. In a pipe-wrench, the combination, with two jaw-plates, of a handle having one end between the jaw-plates, which handle is adjustable at different angles of inclination to the jaw-plates, and of a chain held between the two

plates, and means for holding the free end of the chain, substantially as shown and described.

3. In a pipe-wrench, the combination, with two jaw-plates having a circular or segmental row of apertures on one end, of an adjustable handle held between the jaw-plates by a bolt at the center of the circle of the circular or segmental row of apertures, and of a bolt passed through an aperture in the circular row of apertures and an aperture in the handle-bar, substantially as shown and described.

In testimony that I claim the foregoing as my invention I have signed my name in presence of two subscribing witnesses.

MAURICE QUINLAN.
